UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

METAL FRAMING-JOINT (WELDED).

1,165,048.

Specification of Letters Patent. Patented Dec. 21, 1915.

Application filed August 26, 1914. Serial No. 858,732.

To all whom it may concern:

Be it known that I, HERBERT E. WHITE, a citizen of the United States, residing at Youngstown, in the county of Mahoning 5 and State of Ohio, have invented certain new and useful Improvements in Metal Framing-Joints (Welded), of which the following is a specification.

This invention relates to a novel and practical metal framing joint designed to permanently and rigidly unite the frame members of metal structures such as steel sashes, employed in fireproof building construction.

The important characteristics of a metallic structure, such as contemplated by the present invention, are strength, rigidity, and accuracy of fit of the several frame parts, to provide a construction capable of not only properly supporting the window lights, but 20 also possessing the stability and safety required for fireproofing purposes.

Accordingly, the present invention contemplates the provision of a novel and substantial framing joint for sashes or like structures having great strength and rigidity, besides being easily and economically manufactured without sacrificing any of its advantages, and at the same time preserving a high standard of neatness. That is to 30 say, the invention includes a novel construction of interlocking frame members whose meeting portions may be welded together in such a manner that the bonding metal caused to flow by the welding operation 35 fills into specially provided pockets which contribute materially to the rigid locking together of the frame members.

With the above and other objects in view which will more readily appear as the nature 40 of the invention is better understood, the same consists in the novel construction, combination and arrangement of parts herein-after more fully described, illustrated and claimed.

45 A preferred and practical embodiment of the invention is illustrated in the accompanying drawings, in which—

Figure 1 is a perspective view showing the frame members prior to their being assembled into final position. Fig. 2 is a cross section through the main frame member at the joint, before welding. Fig. 3 is a section at right angles to Fig. 2 before welding, on the line 3—3 of Fig. 2. Fig. 4 is a detail plan view illustrating the preliminary

fit of the V-shaped end portions of the connecting frame members within the V-shaped mortising notches at the sides of the main frame member. Fig. 5 is a view similar to Fig. 2 after the welding operation. Fig. 6 60 is a view similar to Fig. 3 after the welding operation is completed. Fig. 7 is a perspective view of the complete joint.

Like reference characters designate corresponding parts throughout the several figures of the drawings.

For the purpose of illustration, the invention is shown in the drawings as applied to a plurality of frame members of a design adapted to be used in steel sashes, but it 70 will of course be understood that the invention may be applied with equal facility to frame members or bars adapted to other uses.

Referring to the details of construction 75 shown in the several figures of the drawings, it will be observed from Fig. 1 that the improved framing-joint primarily includes a main frame member 1 and the oppositely disposed connecting frame members 2 and 30 80 respectively. In the form illustrated, each of these frame members comprises a symmetrical bar 4 having along one edge portion the oppositely disposed flanges 5 and 6 and the longitudinal edge-rib 7, thus 85 being substantially T-shaped in cross section. In other words, the frame bars are rabbeted to provide the usual seats for the window lights. The bar 4 of the main frame member 1 is provided with an oblong 90 welding hole 8 whose side walls 9 are concaved, so that the hole is substantially of oval design with flattened end portions. The flanges 5 and 6 of this frame member are also preferably provided with substantially 95 V-shaped cut-away portions 10 directly beyond one end of the welding hole 8, thus forming a mortising notch for receiving an end portion of the connecting frame members. The said connecting frame members 100 are of duplicate construction. That is, they are of the same cross-sectional design, and each of the same is provided at its end with a welding tenon 11 which projects from the structural lines of the end of the bar, and 105 is rounded or convexed to provide a crowned butt-portion 12, while the flanges 5 and 6 are beveled at their ends as at 13 to conform approximately to the shape of the notch 10 in the flanges of the main frame 110

member 1. In the latter connection, a special feature is the preliminary fit of the parts as illustrated in Fig. 4 of the drawings. It will be observed therefrom that, 5 preliminarily, the beveling of the elements 10 and 13 is at slightly different angles so that the opposing inclined faces of said elements do not contact over their entire surfaces at once, but meet at their outside edges 10 as indicated at α in said figure, thus contacting only over a limited area at first until fusion begins, whereupon they may be pressed together and a secure weld effected between the three parts.

15 From the foregoing description of the structural details of the frame member, it will be apparent, especially by reference to Fig. 1, that the opposite connecting frame members 2 and 3 are arranged with their 20 tenons 11 in alinement with each other and with the welding opening 8, so that they may be moved into said opening from opposite sides of the bar 4 of the main frame member until their crowned portions 12 25 abut therein, as shown in Fig. 2 of the drawings. The meeting of the crowned portions 12 of the welding tenons in the opening 8 provides metal receiving pockets 14 and 15 respectively above and below the point of 30 contact between the two tenons, and at the same time, because of the concavity of the side walls 9 of the welding opening 8 and the symmetrical sides of the bars 4 of the connecting frame members, other metal receiving pockets 16 and 17 are provided on 35 opposite sides of the meeting welding tenons 11, as clearly shown in Fig. 3 of the drawings. The opening 8 should preferably be so formed at its ends that the welding 40 tenons 11 are just a free fit through it; thus the opening will act as a guide to maintain the abutting tenons in alinement during the welding operation. Furthermore, this construction which permits the crowned portions 45 12 to meet provides abutting contact points of limited area so that a welding temperature may be easily and quickly reached. When the crowned portions 12 of the tenons 11 are inserted in the welding 50 opening 8, and before the welding operation is started, the corner edges 4^a of the connecting frame member are out of contact with the sides 4^b of the bar of the main frame member, and beyond the upper end of the 55 opening 8 a similar space is provided between the beveled ends 13 of the flange portions of the connecting frame members and the notch 10.

With the frame parts in the positions 60 shown in Figs. 2 and 3 of the drawings, the joint is subjected to the action of a welding machine, preferably of the electrical type, and as the joint heats to welding temperature, pressure is applied in the usual manner to the connecting frame members 2 and

3. The welding heat causes the tenons 11 to soften, and under increased temperature and pressure, the metal therein begins to flow and fills into the pockets 14 and 15 respectively above and below the initial point of 70 the contact of the tenons. It also fills into the pockets 16 and 17 at the sides of the abutting tenons. The bars of the opposite connecting frame members are thus united with each other, and during this operation 75 the edges 4^a of the connecting frame members are caused to make a union with the sides 4^b of the bar of the main frame member, and the beveled ends 13 of the flange portions of the connecting frame members 80 are likewise fused into a closed fit within the notch 10. The welding operation may be stopped when the welding tenons have been sufficiently melted to permit the connecting frame members to come into their final position with respect to the sides of the main frame member, or it may be continued until the edges 4^a and 4^b of the bars of the connecting and main frame members respectively, and also the beveled edges 13 of the 85 flange portion of the connecting frame members are fully welded to the body of the main frame member. In either case, the lines of the joint are carefully preserved, thereby insuring an accurate and true assembling and bonding together of the frame members, and preserving their neat appearance. 90

In connection with the welding of the tenons 11, it will be noted that the projecting or crowned portions 12 are initially brought together so that they contact for a comparatively small area at the start of the weld, thus insuring the proper electrical contact between the connecting frame members and greatly facilitating the welding action. Although one of the important features of the invention is making the ends of the tenons 11 convexed, it may be emphasized that the provision of the metal-receiving pockets in the immediate welding zone is of much practical importance, inasmuch as the same provide for accommodating the flow of the plastic metal which would otherwise be crowded out through the fissures of the joint and form rough projections requiring special burnishing operations to remove in order to make the angles of the corners absolutely true so that a window light can have the proper seat. 100 Hence, by reason of the particular construction of the welding tenons and welding hole, the welding operation is perfected through a uniform and effective disposition of the plastic metal, and a better and more 105 finished product obtained. Furthermore, a mechanical feature of practical importance which is involved in the making of this improved joint resides in the fact that although the two members having the welding 110

tenons are welded directly to each other, they will also be very tightly clamped to the other frame member, though not necessarily welded to it, through the contraction 5 of the metal upon cooling after welding. This contraction will cause the two connecting members, which have welded together, to grip the main member very tightly.

From the foregoing it is believed that the many features and advantages of the invention will be readily apparent without further description, and that minor details of construction and design may be resorted to without departing from the spirit of the 15 invention or sacrificing any of the advantages of the construction specified in the appended claims.

I claim:

1. A welded metal framing joint, including a main frame member having therein a laterally enlarged welding hole, and opposite connecting frame members having welding tenons of less thickness than the width of said hole and out of contact with the 25 sides thereof, said tenons being provided with end abutting contact points of limited area.

2. A welded metal framing joint including a main frame member having a bar provided with an oblong laterally enlarged welding opening whose side walls are concaved to produce lateral enlargements of the opening, connecting frame members provided with welding tenons having abutting 35 contact points of limited area and adapted to be welded within the opening of the main frame member.

3. A welded metal framing joint, including a main frame member having therein an oblong laterally enlarged welding opening, and connecting frame members having welding tenons of less thickness than the width of said opening and provided with convexed 40 end portions having abutting contact points of limited area with a clearance from each other above and below said points.

4. A welded metal framing joint, including a flanged main frame member having a welding hole in its web and notches in its 50 flanges, and opposite connecting frame members provided with welding tenons of less thickness than the width of said hole and

having end contact points of limited area, said connecting frame members being also provided with flanges having limited points 55 of contact with the walls of the notches and elsewhere spaced from said walls.

5. A metal framing joint including a main frame member having a bar provided with an oblong welding opening whose side walls 60 are concaved, and opposite connecting frame members having welding tenons provided with convexed end portions adapted to abut within the opening of the main frame member.

6. A metal framing joint including a main frame member formed with an oblong welding hole having concaved sides, and connecting frame members having a bar of symmetrical cross section provided with welding tenons having convexed end portions, said welding tenons adapted to be inserted in the welding hole from opposite sides of the main frame member so that the crowns of their convexed portions meet to provide 75 metal receiving pockets above and below their point of contact, and also providing pockets at the sides of the welding tenons.

7. A welded metal framing joint including a main frame member provided in opposite sides thereof with mortising notches, and connecting frame members having end portions projecting into said mortising notches, said end portions preliminarily contacting with a limited portion only of the 85 main frame member at the notches to facilitate the welding operation.

8. A welded metal framing joint including a main frame member provided in opposite sides thereof with V-shaped mortising notches, and connecting frame members having V-shaped end portions projecting into said notches, said V-shaped end portions preliminarily contacting with a limited portion only of the main frame member at 95 the notches to facilitate the welding operation.

In testimony whereof I hereunto affix my signature in the presence of two witnesses.

HERBERT E. WHITE.
